(57) **CLAIM**

The ornamental design for a vial, as shown and described.

DESCRIPTION

FIG. 1 is a top perspective view of a vial showing our new design;

FIG. 2 is a front elevational view of the vial of FIG. 1;
FIG. 3 is a side elevational view of the vial of FIG. 1;
FIG. 4 is another side elevational view of the vial of FIG. 1;
FIG. 5 is a rear elevational view of the vial of FIG. 1;
FIG. 6 is a top plan view of the vial of FIG. 1;
FIG. 7 is a bottom plan view of the vial of FIG. 1;
FIG. 8 is a top perspective view of the vial of FIG. 1 with the cap removed;

FIG. 9 is a front elevational view of the vial of FIG. 8;

FIG. 10 is a side elevational view of the vial of FIG. 8;

FIG. 11 is another side elevational view of the vial of FIG. 8;

FIG. 12 is a rear elevational view of the vial of FIG. 8;

FIG. 13 is a top plan view of the vial of FIG. 8; and,

FIG. 14 is a bottom plan view of the vial of FIG. 8.

The broken lines in the drawings show structure that is not part of the claimed design, but rather show the environment in which the design is associated, or show portions of the article in which the design is embodied or applied to that are not considered part of the claimed design.

1 Claim, 8 Drawing Sheets
